UNITED STATES PATENT OFFICE.

ROBERT H. IRELAND, OF BROOKLYN, NEW YORK.

GAME.

1,299,731.

Specification of Letters Patent.

Patented Apr. 8, 1919.

Application filed November 2, 1917. Serial No. 199,896.

To all whom it may concern:

Be it known that I, ROBERT H. IRELAND, a citizen of the United States, residing at Ridgewood, Brooklyn, in the county of 5 Kings and State of New York, have invented certain new and useful Improvements in Games, of which the following is a specification.

This invention relates to games and toys, 10 and more particularly to games to be played by moving distinguishable sets of pieces or "men" on the surface of the game board which is marked off into squares similar to a checker board.

15 The general object of the invention is to produce a game apparatus of this character which will facilitate the playing of an interesting, instructive and entertaining game.

Another object is to provide a game which 20 shall represent the conditions of war between two groups of countries and which shall produce certain strategical problems resembling those of actual warfare.

In the form shown in the drawings, the 25 present world war is used as a base for the playing surface.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 35 within the scope of what is claimed without departing from the spirit of the invention.

In the accompanying drawings:

Figure 1 represents a plan view of a game board embodying this invention, and

40 Figs. 2 and 3 are views in perspective of one of each of the respective sets of pieces of contrasting colors employed in playing the game.

In the embodiment illustrated a game 45 board 1 is shown preferably constructed to be folded in the center as shown at 2 like an ordinary checker board. On this board 1, which may be of any suitable material, is a circular map 3 of Europe, the various countries being shown thereon, preferably in colors. The area within the periphery of the circle 3 is marked off into checker squares 4, which may be colored or not, as desired.

Positioned at the center of the circle is 50 located an objective point indicated by H,

designed to represent Hindenburg and which is surrounded by a plurality of circles 5 indicating Germany and her three allies, four circles being shown for each ally, making a total of sixteen, positioned to protect the objective point H. A playing piece 6 shown in Fig. 2 is provided for each circle 5 and they are designed to be moved from the center outward toward the periphery of the circle 3 while those of the Entente, which are 60 shown at 7 in Fig. 3 are moved from the periphery of the circular map 3 toward its center.

The board as shown in Fig. 1 has arranged thereon outside the circular map 3 a plurality of camps 8, six being here shown and designating Russia, America, England, France, Italy and Roumania, respectively. Each of these camps 8 as shown is constructed in the form of concentric bands 9 and 10 between 70 which is a camp prison 11. It is of course understood that the game may be played by a number of players, and when three play the game, one party represents the central powers as Von Hindenburg, and makes all 80 moves as general for the Germans, Austrians, Turks and Bulgarians, using the playing pieces as indicated at 6 in Fig. 2. This party moves first on the map and the other two players follow, one of which represents 85 France, England and America, and the other Italy, Russia and Roumania, using the playing pieces indicated at 7 in Fig. 3. Von Hindenburg plays first then one of the allies follows, and then Von Hindenburg makes 90 another move, followed by another ally, and so on until the allies have captured all the central powers and the Kaiser, which is represented as having been accomplished when one of the allies has gained the center or objective point marked H. 95

In moving the men, all moves are to be played only on the squares 4 and not on the triangles, which are formed adjacent the periphery of the circular map.

100 If four persons are playing it is to be understood that one represents Von Hindenburg, one England and America; one France and Italy, and one Russia and Roumania.

105 Von Hindenburg represented by the playing pieces 6 can advance or retreat as he chooses in the same manner that kings are moved in a game of checkers, but the allies represented by the playing pieces 7 can only 110

advance and never retreat, and they must advance and capture the Kaiser to win the game.

It is to be understood that as many as seven players may engage in this game, and owing to the fact that the map 3 shows the proper geographical location of the countries of Europe, renders the game much more interesting inasmuch as the belligerents on the opposing sides will either become captives or internes when they find it necessary to go into the territory of the neutral countries.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that

the device shown is merely illustrative and that such changes may be made as are within the scope of the claimed invention.

I claim:—

In combination with a plurality of distinguishable sets of pieces, a board having a circular field indicated thereon with the Eastern Hemisphere indicated within said circle and divided into checker squares, a plurality of squares substantially at the center of said field being designated as an objective point to be protected by one set of pieces and attacked by the other, the protecting set of pieces being movable from the center outward and the attacking set from the perimeter inward, and a plurality of camps arranged on said board outside said field.

In testimony whereof I affix my signature in presence of two witnesses.

ROBERT H. IRELAND.
